SENSOR HOUSING FOR AN ALARM SYSTEM

Lloyd R. Bound, Carrollton, Tex., assignor to Texas Instruments Incorporated, Dallas, Tex.

Filed Mar. 23, 1972, Ser. No. 337,598

Term of patent 14 years

Int. Cl. D29—02

U.S. Cl. D72—1 A

FIG. 1 is a perspective view of a sensor housing for an alarm system, showing my new design with the sensor or similar article removed;

FIG. 2 is a front view;

FIG. 3 is a rear view of the housing;

FIG. 4 is a left side view of the housing;

FIG. 5 is a right side view of the housing;

FIG. 6 is a top view of the housing;

FIG. 7 is a bottom view of the housing.

I claim:

The ornamental design for a sensor housing for an alarm system, as shown and described.
